US0D1108748S

(12) **United States Design Patent** (10) **Patent No.:** **US D1,108,748 S**
(45) **Date of Patent:** **** Jan. 6, 2026**

(54) **VACUUM CLEANER**

(71) Applicant: **Peizhong Ding**, Hubei (CN)

(72) Inventor: **Peizhong Ding**, Hubei (CN)

(**) Term: **15 Years**

(21) Appl. No.: **29/968,627**

(22) Filed: **Oct. 17, 2024**

(30) **Foreign Application Priority Data**

May 31, 2024 (EM) 015062185-0005

(51) **LOC (15) Cl.** **15-05**

(52) **U.S. Cl.**

(57) **CLAIM**

The ornamental design for a vacuum cleaner, as shown and described.

DESCRIPTION

FIG. 1 is a front, top perspective view of a vacuum cleaner, showing my new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines in the figures illustrate portions of the vacuum cleaner that form no part of the claimed design.

1 Claim, 8 Drawing Sheets
